TWO-WAY POSITIVE ENGINE HOIST

Charles Bohlen, Jr., New York, N. Y., assignor
to International Motor Company, New York,
N. Y., a corporation of Delaware

Application September 5, 1929
Serial No. 390,503

16 Claims. (Cl. 228—8)

The present invention relates to fire apparatus and embodies, more specifically, an improved vehicle ladder construction with power means to elevate and lower the ladder.

5 The requirements in service of this character are very exacting and it is quite necessary to provide a dependable ladder elevating mechanism which may be operated by mechanical means, at the same time providing auxiliary manual elevating means in order that the ladder may be raised or lowered by hand in the event that the mechanical means should fail. The numerous strains impressed upon the ladder require a highly stable support and the present invention 10 not only provides great stability but incorporates in the operating mechanism, the function of serving as a turn table as well as a fifth wheel having a turning center about the axis of the drive shaft and clutch operating mechanism.

20 An object of the present invention, therefore, is to provide a power operated ladder elevating and lowering mechanism which is simple in construction and operation and highly dependable at all times to function correctly.

25 It is a further object of the invention to provide suitable manual controlling means for the above power mechanism which are conveniently located upon the turn table to facilitate the operation of the ladder.

30 It is further proposed to provide auxiliary hand operating mechanism for raising and lowering the ladder, as well as rotating the turn table with suitable interlocking mechanism between the manually operating mechanism for effecting 35 the above operations and the hand controls for the power operating mechanism.

40 A further object of the invention is to provide a turn table and control stands for controlling the movement of the ladder without impeding the approach or exit to and from the ladder on the platform.

45 A further object of the invention is to provide a ladder elevating and lowering means which gives a relatively low speed for the first twenty degrees of the movement of the ladder, thus picking up the load of the ladder slowly; then a high speed until the last twenty degrees of elevation, at which time the speed is again slackened to enable the ladder to be brought to rest slowly in the desired position.

50 A further object of the invention is to provide an elevating mechanism in which the parts are so constructed that the supporting stresses do 55 not cause binding at the ring bearing of the turn

table, thus permitting free orientation of the turn table.

A further object of the invention is to provide an automatic mechanism for stopping the ladder at its position of maximum elevation, as well as 60 stopping it automatically when it is brought to rest within its cradle.

Further objects of the invention, not specifically enumerated above, will be apparent as it is described in greater detail in connection with the 65 accompanying drawings, wherein:

Figure 1 is a view in side elevation showing a tractor and trailer provided with a ladder and operating mechanism constructed in accordance with the present invention.

70 Figure 2 is a plan view showing the turn table and controls of Figure 1.

Figure 3 is a view in vertical section taken through the controlling mechanism shown in Figure 1.

75 Figure 4 is a view in section, taken on line 4—4 of Figure 3, and looking in the direction of the arrows.

Figure 5 is a view in section, taken on line 5—5 of Figure 3, and looking in the direction of the 80 arrows.

Figure 6 is a view in vertical section taken through the axis of the turn table and showing the elevating mechanism of the present invention.

85 Figure 7 is a view in section, taken on line 7—7 of Figure 6, and looking in the direction of the arrows.

Figure 8 is a detailed view showing the clutch operating mechanism of Figure 6.

90 Figure 9 is a view in section taken on line 9—9 of Figure 6, and looking in the direction of the arrows.

95 Figure 10 is a view in section, taken on line 10—10 of Figure 6, and looking in the direction of the arrows.

100 Referring to the above drawings, *a* designates a tractor which draws a trailer *a*⁶. The trailer may be of the usual ladder supporting type having substructure *a*⁷ and superstructure *a*⁸. These elements form no part of the present invention and further description thereof is believed unnecessary herein. A gear box *a*⁹ is carried on the tractor and driven by the engine thereof, a suitable manual control lever *a*¹⁰ serving to connect or disconnect the drive from the engine to the auxiliary drive shaft *a*³ for supplying power to the ladder elevating mechanism.

105 Shaft *a*³ extends rearwardly to connection *a*⁴ carried on stub shaft *a*⁵ in a clutch housing *b*. The clutch housing is disposed immediately below

the fifth wheel c' on the trailer and lies in the axis thereof, end plates b^6 being provided with suitable bearings b^7 for journalling the stub shaft a^5 and a bottom plate b^8 being provided to give ready access to the interior of the clutch housing. Stub shaft a^5 carries opposed bevel gears b' and b^2 , respectively, these gears floating upon the shaft a^5 . Clutches b^3 and b^4 , of well known form, are provided for locking the respective gears b' and b^2 to the shaft a^5 . These clutches b^3 and b^4 are selectively operated by a clutch operating mechanism to be described hereinafter. A driven gear b^5 is carried within housing b and engages the bevel gears b' and b^2 , the gear b^5 being mounted upon a vertically disposed drive shaft d .

A relatively stationary extension d' is secured to the clutch housing b at d^2 and serves as a housing for shaft d , the two being coaxial. Bearings d^3 are provided to mount the shaft d in the extension.

The fifth wheel c' is rotatably associated with an annular bearing member c' upon which bolts c^4 secure a ring bearing c^2 . The ring bearing c^2 supports the entire ladder and elevating mechanism upon the trailer and fifth wheel, ball bearings c^5 being provided to take the thrust of the table when the ladder is elevated to an angle such that its gravitational component of load falls outside the turn table. Ball bearings x rotatably mount the bearings c^2 upon the member c' . A gear box e is provided with pedestals e' which are secured to the ring bearing c^2 by bolts e^2 . Gear box e carries an auxiliary housing f having a downward extension f' which is received within the upwardly extending housing d' . The fitting between portions d' and f' is such as to permit relative movement therebetween about their common axis and the shaft d extends through, and is journaled at f^2 within the extension f' , the extremity of such shaft carrying a bevel pinion d^4 . The turntable is thus adapted to be rotated in a horizontal plane about a vertical axis in order that the ladder mechanism carried thereby may be properly directed.

A worm shaft e^3 carries a worm e^4 and is journaled in the gear box at e^5 and e^6 . Shaft e^3 extends outwardly into the auxiliary housing f and carries a bevel gear e^7 which meshes with the bevel pinion d^4 .

Gear box e is provided with a cover e^8 and shafts e^9 and e^{10} are journaled in the box. A worm wheel e^{11} is mounted on shaft e^9 and engages the worm e^4 , thus serving as a driving connection between shafts e^3 and e^9 . Driving pinions e^{12} are carried on the shaft e^9 and engage gears e^{13} on the shaft e^{10} .

Crank arms g are keyed on the extremities of shaft e^{10} and are pivotally connected at their extremities to links g' which are pivoted to the ladder h at h' . The power means for elevating or lowering the ladder include, therefore, the following elements. Drive shaft a^3 transmits power to a selected bevel pinion b' or b^2 , the selected one of which drives the bevel gear b^5 . From gear b^5 , the drive is transmitted through shaft d and bevel pinion d^4 to bevel gear e^7 and shaft e^3 . The worm e^4 on shaft e^3 drives the worm wheel e^{11} and shaft e^9 while driving pinions e^{12} drive gears e^{13} and shaft e^{10} . Cranks g transmit the rotary motion of shaft e^{10} to links g' and ladder h . A control platform i is carried by the bearing c^2 and A-brackets j are anchored to ring bearing c^2 and provided, at their upper extremities, with bearings j' upon which the ladder h is journaled.

A control pedestal k is secured to the bearing c^2 by bracket k' and includes a clutch housing k^2 and a control housing k^3 . Shaft k^4 is carried axially within the housing k and is slidably mounted within sleeves k^5 and k^6 . Sleeve k^5 is formed with a worm wheel k^7 , while sleeve k^6 is formed with a bevel pinion k^8 . A stub shaft k^9 is journaled in the clutch housing k^2 and extends axially of shaft k^4 , the upper end thereof being formed with a cup-shaped recess k^{10} having clutch teeth k^{11} and the lower end thereof carrying a spur gear k^{12} which engages teeth c^3 on the annular supporting member c' .

Bevel pinion k^8 is formed with a recess having clutch teeth k^{13} and shaft k^4 is provided with male clutch elements k^{14} and k^{15} for engaging the respective female clutch elements k^{11} and k^{13} , respectively.

The control housing k^3 carries a transversely mounted shaft k^{16} provided with a worm k^{17} for engaging the worm wheel k^7 . A hand wheel k^{18} is keyed to the shaft k^{16} and provided with an arm k^{19} , while the opposite extremity of shaft k^{16} is provided with a crank arm k^{20} and an arm k^{21} . The motion of either crank k^{20} or hand wheel k^{18} is transmitted to shaft k^4 through worm k^{17} and worm wheel k^7 .

In order that the ladder may be elevated or lowered manually, the motion of shaft k^4 is transmitted to a shaft section l journaled in an extension k^{22} on the clutch housing k^2 . A bevel gear l' is keyed to the shaft l and the motion of the shaft is transmitted through a universal joint l^2 to a shaft section l^3 which is journaled in an extension f^3 of the auxiliary housing f . A bevel pinion l^4 is keyed to the extremity of shaft section l^3 and engages bevel pinion d^4 in the auxiliary housing f . When shaft k^4 is raised, clutch member k^{15} engages the clutch member k^{13} to lock sleeve k^6 upon shaft k^4 . In this manner, the rotation of shaft k^4 is transmitted to the shaft section l and continued rotation thereof elevates or lowers the ladder depending upon the direction of such rotation. It will be understood, of course, that both clutches b^3 and b^4 are disengaged during such manual operation.

Within the control housing k^3 , a web k^{23} is formed and a stud shaft k^{24} is mounted in one wall of the housing and the web k^{23} . A manually operable lever k^{25} is journaled on stub shaft k^{24} and carries an extension k^{26} provided with an inwardly extending roller k^{27} which engages a groove k^{28} in a collar on the upper extremity of shaft k^4 . In this manner, shaft k^4 may be raised or lowered to engage, selectively, pairs of clutch elements k^{13} and k^{15} or k^{11} and k^{14} . When the shaft k^4 is lowered to engage clutch elements k^{11} and k^{14} , shaft section k^9 is rotated with shaft k^4 and the turn table is oriented as desired.

The control for clutches b^3 and b^4 is carried by the control pedestal k and constitutes a manually operable lever k^{29} which is keyed to stub shaft k^{24} . On the outer extremity of shaft k^{24} , a crank arm k^{30} is secured, this arm being connected to a link k^{31} which is secured to one arm of a bell crank lever k^{32} . A second link k^{33} is connected to the other arm of the bell crank lever k^{32} and the other extremity of the second link is connected to a crank arm k^{34} which is mounted upon a shaft k^{35} , journaled in the auxiliary housing f . Shaft k^{35} extends within the housing f and carries a crank arm k^{36} which is formed with an inwardly extending lug k^{37} for engaging a groove m formed in a collar on

a shaft m' . Shaft m' is supported in the turning axis of the turntable and extends axially through shaft d , carrying at the lower extremity thereof, yoke m^2 . Shaft d includes a section d^{12} which is splined thereto at d^{13} . Yoke m^2 may be formed with diagonal reinforcing webs m^4 . Extending inwardly from the sides of the clutch housing b , are bosses b^9 which mount, pivotally, bell crank members b^{10} connected by a spacing member b^{11} . Upwardly extending arms b^{12} formed on the bell cranks b^{10} are provided with inwardly extending lugs b^{13} which engage the double male clutching member b^{14} for selectively engaging the clutch members b^3 and b^4 . Movement of the arms b^{12} in one direction causes one of the clutches to be engaged, while movement in the opposite direction causes the other clutch to be engaged. Lateral arms b^{15} , formed on the bell crank members b^{12} , have heads b^{17} engaging slots b^{16} formed in the extremities of the yoke-shaped member m^2 to transmit the vertical movement thereof to the bell crank levers b^{12} . Vertical slots b^{18} are formed in the yoke m^2 to receive the bosses b^9 and thus guide the movement of the yoke.

Supporting arms e^{14} suspend gear box e and cover e^8 upon the shaft j' , the reaction to the lifting force incidental to the elevating or lowering of the ladder h , thus being taken by the shaft j' instead of being impressed upon the ring bearing c^2 with consequent jamming thereof. From the disposition of the shaft centers j' and e^{10} , and the lengths of the links g' and crank arms g , it will be apparent that no toggle action between such members can ever take place. The lines between the centers of shafts j' , e^{10} and h' will never lie in a common plane and thus an overhanging load tending to capsize the vehicle can never exist.

In order that the speed of raising or lowering may be accelerated at will, and controlled from the control pedestal k , a manual lever k^{38} is carried by a stub shaft k^{39} journaled within the control housing k^3 . An arm k^{40} , secured to the stub shaft k^{39} is connected to a cable k^{41} which passes over a roller k^{42} carried by the extension k^{22} and is connected to an arm e^{15} pivoted to a lug formed on the gear box e . A second arm e^{16} is formed on the arm e^{15} and is provided with a ball head for engaging a recess d^4 in a sleeve d^5 which is slidably keyed at d^8 to housing d' . A spring d^7 normally urges the sleeve downwardly and lug d^8 , formed on the sleeve d^5 , is connected to a link d^9 which, in turn, is connected to a lever d^{10} , secured to a shaft d^{11} . Shaft d^{11} is journaled in a bracket b^{18} and carries an arm d^{12} which is suitably connected to the throttle of a tractor engine which drives shaft a^3 . In this manner, the speed of the engine and consequently the speed of elevation of the ladder may be conveniently controlled.

In order that the ladder may be automatically stopped in its position of maximum elevation, as well as its position of rest within the cradle of the trailer, a segment n is secured to shaft e^{10} and is of an arc equivalent to the maximum number of degrees or length of arc through which the ladder may be operated in moving from the operative to inoperative position or vice versa less than the number of degrees or length of arc of the movable lug n^{11} . A sleeve n' is journaled on the shaft e^{10} and is provided with a lug n^2 to which a two part link n^3 is connected, the parts being pivoted at n^{12} . This link is carried in a sleeve n^4 which is journaled in a boss n^5 , formed in a cover

e^8 and a head n^6 is formed on the extremity of link n^3 and provided with a spiral groove n^7 . A nut n^8 , formed with rollers n^9 , extending within the grooves n^7 , is formed with a lever which is connected to a link n^{10} . This link is provided with a forked extremity to engage a head m^3 on shaft m' . When the ladder reaches a position of maximum elevation, a lug n^{11} , carried by the sleeve n' , is engaged by the appropriate extremity of sector n and causes the link n^3 to be moved forwardly. Such movement causes rollers n^9 and nut n^8 to be rotated with respect to the boss n^5 and the link n^{10} is accordingly either elevated or lowered. This motion is transmitted to the clutch controlling shaft m' and causes disengagement of the clutches b^3 and b^4 when the ladder reaches either extremity of movement.

It will be seen from Figure 2, that the control pedestal k is offset with respect to the center line of the ladder, thus facilitating access thereto. The elevating mechanism is combined with the related structure in such manner that it functions not only as a turntable and hand wheel, but it includes the clutch operating shaft and drive shaft to raise and lower the ladder. Auxiliary hand operating mechanism is incorporated in the structure and a detent k^{42} , between manual levers k^{25} and k^{29} serves as an interlock to prevent operation of the manual mechanism, while the power mechanism is operating.

The operation of the mechanism will be readily apparent from the foregoing description and is accomplished by means of the primary clutch lever a^2 which connects the power take-off a^3 to the source of power a' . After engaging this clutch mechanism, the ladder may be controlled from the platform i by means of the controlling mechanism described above. Should the source of power fail, the operation of the ladder may be effected manually by means of wheel k^{18} by suitable manipulation of the control lever k^{25} which selectively engages the clutching mechanism in housing k^2 to raise or lower the ladder. Control lever k^{38} is connected to the engine throttle and thus facilitates the speed with which the ladder is elevated and lowered by means of the power source. Lever k^{29} controls the clutches b^3 and b^4 through the mechanism including links k^{31} and k^{33} to actuate the shaft m' selectively. In this fashion, the engine power may be utilized to elevate the ladder by suitable manipulation of the control lever k^{29} and the segment and cam n and n' automatically preventing the mechanism from operating after the ladder has been elevated to its maximum position. Reverse movement of the ladder is effected in an obvious fashion and such movement is also automatically stopped when the ladder reaches its cradle position.

All of the controls are conveniently located on the turntable platform and the ladder is controlled automatically after the operation of the power means has been initiated. The supporting of the gear box upon the ladder fulcrum prevents binding of the ring bearing since the load stresses are neutralized and carried entirely by the gear box and elevating links.

While the invention has been described in connection with the specific construction shown in the accompanying drawings, it is not to be limited, save as defined in the appended claims.

I claim as my invention:

1. A device of the character described comprising a turntable, a power shaft disposed axially of the turntable, a clutch driving the shaft, a clutch operating member disposed axially of the shaft, a

- gear box carrying a ladder elevating shaft, means in the box to drive the shaft from the power shaft, an axially movable shaft in the box, a connection between the axially movable shaft and 5 the clutch operating member, a sleeve rotatable on the ladder elevating shaft and connected to the axially movable shaft, a dog on the sleeve, and a segment on the elevating shaft to engage the dog.
2. A device of the character described comprising 10 a turntable, a power shaft disposed axially of the turntable, a clutch driving the shaft, a clutch operating member disposed axially of the shaft, a gear box carrying a ladder elevating shaft, means in the box to drive the shaft from the power shaft, 15 an axially movable shaft in the box, a connection between the axially movable shaft and the clutch operating member, and means actuated by the ladder elevating shaft for moving the last mentioned shaft axially.
- 20 3. A device of the character described comprising a turntable, a power shaft disposed axially of the turntable, a clutch driving the shaft, a clutch operating member disposed axially of the shaft, a ladder elevating shaft, and means actuated by the 25 ladder elevating shaft for operating the clutch operating member upon predetermined movement of the ladder.
4. A device of the character described comprising 30 a turntable, a ladder supports on the turntable, a ladder hinged to the supports, a gear box hung at one end on the ladder hinge and supported, at the other end, on the turntable, a power shaft journaled in the gear box, a crank arm connected to the shaft, and an arm connecting the 35 crank arm and ladder.
5. A device of the character described comprising 35 a turntable, ladder supports on the turntable, a ladder hinged to the supports, a gear box connected to the hinge of the ladder and carrying a power shaft, and means connecting the power shaft and ladder to elevate the latter, whereby the thrust due to elevating forces will be taken by the hinge of the ladder.
6. A device of the character described comprising 40 a turntable, a ladder hinged thereon, a drive shaft carried by the turntable, a crank arm carried by the shaft, and an arm pivoted to the crank arm and to the ladder, the pivot points of the last named arm lying in a plane passing through the 50 axis of the shaft when the ladder is in its normally lowered position.
7. A device of the character described comprising 55 a turntable, a ladder hinged thereon, drive means carried by the turntable, an arm pivoted to the ladder, and means connecting the arm and the drive means to elevate the ladder slowly at the beginning and end of its movement, and more rapidly in the intervening movement.
8. A device of the character described comprising 60 a turntable, a ladder mounted thereon, means to elevate the ladder, power means to operate the elevating means, a power take-off connected to the power means, a manually operable shaft, a clutch connecting the power take-off to the manually operable shaft, means to rotate the turntable, a second clutch connecting the turntable rotating means to the manually operable shaft, and means to move the shaft axially to engage the clutches selectively and to position the shaft in an intermediate non-clutch engaging position.
9. A device of the character described comprising 65 a turntable, a ladder mounted thereon, means to elevate the ladder, power means to operate the elevating means, a power take-off connected to the power means, a manually operable shaft, a clutch connecting the power take-off to the manually operable shaft, means to rotate the turntable, a second clutch connecting the turntable rotating means to the manually operable shaft, and means to move the shaft axially to engage the clutches selectively. 80
10. A device of the character described comprising 85 a turntable, a ladder mounted thereon, means to elevate the ladder, power means to operate the elevating means, a power take-off connected to the power means, a manually operable shaft, a clutch connecting the power take-off to the manually operable shaft, means to rotate the turntable, and means to move the shaft axially to engage the turntable rotating means. 90
11. A device of the character described comprising 95 a turntable, a ladder mounted thereon, means to elevate the ladder, power means to operate the elevating means, a manually operable power shaft, a power take-off connected to the power means, a clutch connecting the power take-off to the manually operable shaft, and means to move the manually operable shaft axially to connect it selectively with the power take-off through the clutch. 100
12. A device of the character described comprising 105 a turntable, a ladder mounted thereon, means to elevate the ladder, power means to operate the elevating means, and common manual means to operate the elevating means and rotate the turntable. 110
13. A device of the character described comprising 115 a fifth wheel, a turntable rotatably carried thereby, a ladder operating shaft coaxial with the turntable, a clutch carried with the fifth wheel and supplying power to the ladder operating shaft, and a clutch operating shaft coaxial with the ladder operating shaft. 120
14. A device of the character described comprising 125 a turntable, a ladder mounted thereon, means to elevate the ladder, drive means coaxial with the axis of the turntable for operating the elevating means, a sleeve surrounding the drive means and movable axially thereof, means actuated by the sleeve to vary the speed of the drive means, and means on the turntable to actuate the sleeve. 130
15. A device of the character described comprising 130 a turntable, a ladder mounted thereon, means to elevate the ladder, power means to operate the elevating means, manual means to operate the elevating means, and an interlock between the power and manual means to prevent the simultaneous connection of the manual and power means to the ladder elevating means. 135
16. A device of the character described comprising 135 a turntable, a ladder mounted thereon, means to elevate the ladder, drive means coaxial with the axis of the turntable for operating the elevating means, means mounted concentric with the turntable for reversing the drive means, means mounted on the turntable for controlling the reversing means, and means on the turntable for controlling the speed of the driving means. 140

CHARLES BOHLEN, JR.
